POPCORN DISPENSER

Willis E. Clark and John E. Beall,
Los Angeles, Calif.

Application March 4, 1950, Serial No. 8,326

Term of patent 14 years

(Cl. D52—3)

To all whom it may concern:

Be it known that we, Willis E. Clark and John E. Beall, both citizens of the United States, and both residing at Los Angeles, State of California, have invented a new, original, and ornamental Design for a Popcorn Dispenser, of which the following is a specification, reference being had to the accompanying drawing, forming a part thereof.

Fig. 1 is a perspective view of a popcorn dispenser embodying our new design.

Figs. 2, 3 and 4 are plan, front, and side views respectively of the dispenser.

We claim:

The ornamental design for a popcorn dispenser, substantially as shown.

WILLIS E. CLARK.
JOHN E. BEALL.
